UNITED STATES PATENT OFFICE.

FRANCIS W. CARPENTER, OF ST. PAUL, MINNESOTA.

DRUM SUPPORT AND DETACHABLE DRIVING CONNECTION FOR WASHING MACHINES.

Application filed August 7, 1922. Serial No. 580,882.

To all whom it may concern:

Be it known that I, FRANCIS W. CARPENTER, a citizen of the United States, residing at St. Paul, in the county of Ramsey and State of Minnesota, have invented certain new and useful Improvements in Drum Supports and Detachable Driving Connections for Washing Machines; and I do hereby declare the following to be a full, clear, and exact description of the invention, such as will enable others skilled in the art to which it appertains to make and use the same.

My present invention relates to washing machines of the rotary drum type and provides an extremely simple and highly efficient drum support and driving connection that permits the drum to be quickly and easily detached from or attached to the driving connection. Generally stated, the invention consists of the novel construction, arrangements and combinations of parts hereinafter described and defined in the claim. A companion application filed by me of even date herewith and entitled "Washing machine," illustrates a novel mechanism for rotating the drum alternately first from one direction and then the other, but the present application is applicable in connection with any suitable drum-rotating mechanism.

In the accompanying drawings, which illustrate the invention, like characters indicate like parts throughout the several views.

Referring to the drawings:

Fig. 1 is a vertical section taken centrally through the tank casing and drum of the washing machine of the rotary drum type, some parts being shown in full and some parts being broken away;

Fig. 2 is a fragmentary section taken approximately on the line 2—2 of Fig. 1;

Fig. 3 is a fragmentary section taken approximately on the line 3—3 of Fig. 1; and

Fig. 4 is a detail in section on the line 4—4 of Fig. 3, showing also a portion of the tank and drum-driving shaft.

The tank 5 of the washing machine is preferably an approximately semi-cylindrical sheet metal structure placed within a sheet metal casing or cabinet 6. The upper edges of the vertical plates of the case 6 are shown as reinforced by angle bars 7 and the tank 5 is provided with outturned flanges that rest on these angle bars. Clamping bars

8 are placed on the outturned flanges of the tank and machine screws 9 are passed through said clamping bars, said outturned flanges and the inwardly projecting flanges of the angle bars 7. This construction very securely anchors the tank to the case and makes the same readily detachable from said case.

A cylindrical drum 10 that works within the tank 5 and rotates on a horizontal axis, may be of any suitable structure but, as shown, is made up of sheet metal heads and a perforated sheet metal cylinder that will be formed with the customary door. One head of the cylinder, at the axis of the drum, has an outwardly projecting trunnion 11 and to the outer surface of the other drum is rigidly secured a bearing plate 12 that has an outstanding triangular coupling flange 13. This triangular flange preferably forms the outline of an equi-lateral triangle, the center of which is at the axis of the drum. One of the three sides of the triangular flange 13 is reduced in width so that it preferably has only about one-half the width of the other two sides, (see particularly Figs. 3 and 4), and this is done for an important purpose which will presently appear.

To receive the trunnion 11, the adjacent side of the tank 5, on its inner surface, is provided with a rigidly secured bearing 14 that is provided with an upwardly flaring trunnion seat preferably afforded by a flange 14^a that not only diverges upwardly but recedes from the drum head toward the adjacent side of the tank.

For rotating the drum, a driving shaft 15 is extended through that side of the tank 5 that is adjacent to the triangular flange or seat 13. To afford a water-tight journal for the shaft 15 in the side of the tank, I provide a bearing hub 16 which has a packing gland 17 and a pocket 18, which latter is adapted to contain a suitable packing material. The bearing hub 16 has an outstanding flange between which and the adjacent side of the tank 5 is interposed a suitable gasket 19 which may, for example, be of a material known as "rainbow packing." Clamping screws 20 are passed through perforations in the outstanding flange of the hub 16 and through relatively large holes in the side of the tank and are screwed into an annular metallic clamping ring 21.

To the inner end of the driving shaft 15 is secured a triangular driving head 22 that will fit with slight clearance within the triangular flange 13 of the drum. As a very efficient means for detachably but rigidly securing this triangular driving head 22 to the driving shaft 15, the latter is tapered to fit a tapered seat formed in the center of said head and a machine screw 23 is counter-sunk into said head and screwed into a seat at the end of said shaft. Also, an oblique key 24 is seated in the tapered portions of the shaft and head, (see Fig. 4). This means secures the driving head to the driving shaft in a manner that will prevent any slack or looseness between the two, even under the considerable strains produced by reversal of the drum-driving mechanism.

The novel relative arrangement of the parts described and the importance thereof will be observed particularly by directing attention to Fig. 1, but here it will be noted that when the drum is in horizontal working position, as shown by full lines in said view, the trunnion 11 will find a suitable bearing in the crotch of the flange 14^a and the triangular flange 13 will then be telescoped completely around, will rest upon and will be rotatively interlocked to the triangular driving head 22 so that when the shaft 15 is rotated, the drum will be rotated therewith regardless of the direction in which said shaft is rotated.

When it is desired to remove the drum from operative position and to take the same out of the tank, the drum is stopped in position with the reduced portion 13^a of the triangular flange 13 at the bottom or turned downward into a horizontal position, as shown in the drawings. When this is done, the drum may be moved first by tilting the same in the position indicated by dotted lines in Fig. 1, which carries the reduced flange 13^a slightly inward of the inner face

of the triangular head 22, thus permitting 45 the drum to be lifted out of the tank.

When the drum is to be applied in the tank and coupled with the driving shaft, the operation will be reversed, that is, the drum will be lowered while tilted into a position 50 indicated by dotted lines in Fig. 1, and then the trunnion-equipped end of the drum will be dropped down to its seated position in the open seat afforded in the flange 14^a, and this latter operation carries the reduced flange 55 13 under the lower surface of the driving head 22, thus interlocking said drum for rotation with the driving shaft 15.

This construction, while very simple, has been found very efficient for the purpose 60 had in view. It is strong and durable and has no parts that will get out of operative condition. It permits the drum to be very quickly and easily applied in working position or removed from working position.

What I claim is:

The combination with a tank and a rotary drum, of a driving shaft extended through the side of said tank and provided at its inner end with a triangular driving head, said drum at the axis of one head having a trunnion and the adjacent wall of said tank having an open seat affording a bearing for said trunnion, said drum at the axis of its other head having a triangular seat 75 formed by a triangular outstanding flange, one of the walls of which flange is of greatly reduced width, which flange detachably fits around said driving head, its reduced wall permitting said flange to be disengaged from 80 said head and the drum to be detached from said driving shaft and removed from said tank, first by lifting the trunnion-equipped end of said drum to axially incline the drum and then lifting said drum from position.

In testimony whereof I affix my signature.

FRANCIS W. CARPENTER.
